(57) **CLAIM**

We claim the ornamental design for an aerosol generator, as
shown.

DESCRIPTION

FIG. 1 is a top perspective view of an aerosol generator.
FIG. 2 is a top view of the aerosol generator depicted in FIG.
1.

FIG. 3 is a bottom view of the aerosol generator depicted in
FIG. 1.

FIG. 4 is a front view of the aerosol generator depicted in
FIG. 1.

FIG. 5 is a rear view of the aerosol generator depicted in
FIG. 1.

FIG. 6 is a right side view of the aerosol generator depicted in
FIG. 1.

FIG. 7 is a left side view of the aerosol generator depicted in
FIG. 1; and,

FIG. 8 is a bottom perspective view of the aerosol generator
depicted in FIG. 1.
